ATTORNEYS.

UNITED STATES PATENT OFFICE.

GEORGE L. CASTNER, OF MEMPHIS, TENNESSEE.

COIN-PACKAGE.

SPECIFICATION forming part of Letters Patent No. 400,052, dated March 26, 1889.

Application filed December 13, 1887. Serial No. 257,796. (No model.)

To all whom it may concern:

Be it known that I, GEORGE L. CASTNER, of Memphis, in the county of Shelby and State of Tennessee, have invented a new and Improved Coin-Holder, of which the following is a full, clear, and exact description.

My invention is an improvement in the class of coin-holders which are formed of paper or other thin flexible material, and adapted to confine the coin so that a considerable portion thereof is exposed to view.

The construction of the holder is as herein-after described and claimed.

In the accompanying drawings, Figures 1, 2, 15 and 3 are perspective views of slightly-differing forms of my invention; and Fig. 4 is a similar view of a modification.

Those forms shown in Figs. 1, 2, and 3 are each composed of two parts—namely, the body 20 or coin receiver and holder proper, 1, and the binder or binding-strip, 2. Both parts are made of paper, that being a material which may be easily torn, for the purpose of releasing the coins when desired. The body or 25 holder proper, 1, is made by bending a strip into the form of a rectangle, and the binding-strip 2 is pasted to the back of such holder 1, so that it is normally at right angles to the axis of the opening through the holder 1.

30 As shown in Figs. 1 and 3, the ends of the body-strip 1 are enlarged on one side, and the binding-strip 2 is pasted on them. Such enlargement of the ends affords a larger area for adhesion of the binder 2. As shown in 35 Fig. 2, the ends of the body-strip 1 are not enlarged or extended and abut at a point opposite that where the binding-strip 2 is attached. Fig. 3 shows a construction similar to Fig. 1, save that the upper outer corners of 40 the body-strip are rounded instead of square.

Fig. 4 shows the holder proper made of a broad backing-piece, 3, and a narrow strip, 2. The latter is pasted to part 3 at suitable intervals, the intervening portions of the said 45 strip being bent in the form of three sides of a rectangle. The part 3 is creased vertically,

at points between the binding-strips 2, to facilitate tearing off a portion of the packet or holder. On the back of the part 3, opposite each rectangular pocket thus formed by the strip 50 1, a binding-strip, 2, is pasted, as shown. At the left-hand end one of the binding-strips is shown in dotted lines folded over coins placed in the contiguous pocket and pasted to the front of strip 1. In this case, as in that 55 of the device constructed, as shown in the other figures, the binding-strip and body-strip are made of less width than the coins designed to be contained in the holder proper, and the latter is also of less cubical capacity than the 60 largest cross-section of the coins, so that a portion of the edges and the sides of the outer coins remain visible when secured in the holder.

Each pocket, whether the device be constructed as shown in one figure or another, is made of a size adapted to contain a specific number of coins of the same denomination; but of course the pockets may be made of various sizes regardless of this idea. 70

What I claim is—

1. The improved coin-holder composed of the binding-strip 2 and the holder proper, 1, which is made of a strip whose ends abut each other, the said binding-strip being united to 75 the said ends at right angles to the holder 1, and both the parts 1 and 2 being made of less width than the coins the holder is designed to contain, and the holder proper, 1, being made of less cubical capacity than the largest 80 cross-section of the coins to be contained in it, as shown and described.

2. The combination of a series of binding-strips, 2, a backing-piece, 3, to which they are pasted, and the strip 1, bent, as shown, and 85 pasted to the part 3 at points intervening the binding-strips 2, as specified.

GEORGE L. CASTNER.
